D 13,320

UNITED STATES PATENT OFFICE.

RIVERIUS MARSH, OF NEW BRUNSWICK, NEW JERSEY.

DESIGN FOR A LAMP-BRACKET.

SPECIFICATION forming part of Design No. 13,320, dated September 26, 1882.

Application filed August 28, 1882. Term of patent 3½ years.

To all whom it may concern:

Be it known that I, RIVERIUS MARSH, a citizen of the United States, residing at New Brunswick, in the county of Middlesex and State of New Jersey, have invented and produced a new and original Design for Lamp-Brackets, of which the following is a specification, reference being had to the accompanying photographs, forming a part thereof.

10 The photograph represents a side view of my newly-designed lamp-bracket.

The leading features of my design consist in a broken tree with one branch left standing, on which are side branches. On the ends of 15 these side branches fruit or leaves are represented. On the arm or lower part of the bracket a rustic fence or gate is represented. Above and partly over this fence a buck or deer is shown in the act of leaping over the 20 fence. At the end of the fence a plant with foliage and flowers is shown. The different parts above described are united at certain points, thus forming a scroll-bracket. Directly below and attached to this bracket is an ornamental piece or bar extending beyond the 25 scroll-work. At the outer end of this piece

and below it is a key-shaped piece, and above it a lamp-rest, as shown. At the large end of the bracket, and extending out from the broken trunk of the tree, is a hook or projection for 30 fastening or hanging the bracket to the wall-piece. On the stump of the tree is a dove with outstretched wings. The wall-piece has a dove with outstretched wings on the top and ornamental leaves at the bottom, and with 35 an eye near the center to receive the hook or projection on the back of the bracket.

These brackets can be used for various purposes.

I claim—

40 The design for a lamp-bracket herein shown and described, the same consisting of the broken tree and branches, the rustic fence, the buck or deer leaping the fence, the plant and foliage, the ornamental bar-key and lamp-rest, and 45 the dove on the stump of the tree, also the back piece with a dove at the top and the ornamental leaves at the bottom.

RIVERIUS MARSH.
